UNITED STATES PATENT OFFICE.

FREDERICK SLOCUM CULVER, OF TAUNTON, MASSACHUSETTS.

THREAD-BOARD-GUIDE-WIRE HOLDER.

1,114,341.

Specification of Letters Patent.

Patented Oct. 20, 1914.

Application filed October 8, 1913. Serial No. 794,180.

To all whom it may concern:

Be it known that I, FREDERICK S. CULVER, a citizen of the United States, residing at Taunton, in the county of Bristol and State of Massachusetts, have invented a new and useful Improvement in Thread-Board-Guide-Wire Holders, of which the following is a specification.

This invention pertains to certain new and useful improvements in thread board guide wire holders, and the primary object thereof is to improve and simplify the finger head construction and to provide new and improved means for positively holding the head either in operative or inoperative position, which means is of simple and efficient character, and which allows the head to be easily moved from one position to the other.

Further, the invention resides in certain details of construction and combination of parts, which will be more fully set forth in the course of the following specification.

In the drawings—Figure 1 is a side elevation of the invention applied to a thread board rail, the latter being shown in fragment and in section, the finger head being illustrated in operative position. Fig. 2 is a similar view showing the head in raised or inoperative position. Fig. 3 is a bottom plan view of the invention, in detached relation to the board, and Fig. 4 is a perspective view of the head, the guide wire being omitted.

In accordance with the present invention the head is preferably formed of a section of sheet metal, bent to form a trough-like structure possessed of a body 1, sides 2, a front end 3, and a rear wall 4, the latter extending beyond the free edges of the sides 2 and formed of a continuation of the body. The front end 3 is provided with a concave seat 5 in which the shank 6 of the wire thread guide 7 is received. The rear or inner end of the shank 6 is bent into a U-shaped portion 8, the legs of which portion engage the inner faces of the sides 2 to thereby hold the shank against lateral movement relative to the head in which regard the seat 5 also acts to further prevent lateral movement of the front end portion of the shank 6 as is evident from Fig. 3 of the drawings.

The tail of the holder is formed of a member 9 which is secured to the under face of the thread board rail T and which has a pair of perforated forwardly projecting ears 10, which latter receive the rear ends

of the sides 2, of the head, said rear ends of the sides 2 having apertures 11 that align with the perforations of the ears 10 so as to receive a pintle or pin 12, which latter serves to pivotally connect the head to the tail. The tail is also provided with a pair of spaced depending perforated lugs 13 which receive a straight spring member 14, the member 14 having a driving fit in the perforations of the lugs, so as to be secured frictionally therein. The front or free end of the member 14 bears against the free edge of the wall 4 at the rear of the head, so as to exert sufficient tension on said wall in order to hold the head either in the position depicted in Fig. 1 or that of Fig. 2, the member 14 bearing on the wall 4 only sufficiently to effectively hold the head in the positions shown, so as to allow the head to be moved from one position to the other with the expenditure of comparatively slight force. A nut and screw 15 is employed to secure the U-shaped portion of the thread guide in position relative to the head.

From the above it will be apparent that the head can be easily stamped from a single piece of sheet metal which involves minimum expense and labor. Further, the entire structure is simple, and involves a minimum of parts, which can be easily and quickly replaced, if damaged or rendered by wear unfit for further service. In addition since the spring and associated parts face downwardly, they are subjected to protection against injury in an obvious manner.

Having thus described my invention, I claim as new and desire to secure by Letters Patent:

1. In combination with the thread board rail, a tail member secured to the under face thereof, a pair of spaced perforated ears on the tail member projecting forwardly therefrom, a pair of spaced perforated depending lugs on the tail member, a straight spring member engaged in the perforations of said lugs, a head formed of sheet metal blank having a front end formed with a concave seat, sides, and a rear wall which latter projects beyond the sides and is engaged at its free edge by the front end of the spring member, said sides at their rear ends being perforated and received in the space between the ears, a pin passed through the perforations of the ears and head sides, and a thread guide secured to the head and

having the shank thereof engaged in said seat and having a U-shaped rear portion which engages the confronting faces of the sides of the head.

- 5 2. In combination with a tail member for
securement to the thread board rail, a pair
of perforated lugs depending from said tail
member, a straight spring secured in the
perforations of the lugs, a head pivoted to
the tail member, an abutment on the rear
end of the head on which the free end of the
spring bears, a seat at the front end of the
head, and a thread guide engaged in the
seat.
- 15 3. In a device of the type set forth, a tail
member, a head pivoted to the tail member

and formed from a single piece of sheet
metal shaped to provide sides, a front end
formed with a seat, and an abutment at its
rear end formed from a continuation of the 20
body of the metal, a thread guide carried by
the head having a part thereof engaged in
said seat, and a spring carried by the tail
member and engaged with said abutment.

In testimony whereof I have signed my 25
name to this specification in the presence of
two subscribing witnesses.

FREDERICK SLOCUM CULVER.
